UNITED STATES PATENT OFFICE.

ANDREW J. PENNINGTON, OF TULSA, OKLAHOMA, ASSIGNOR TO U. S. COMPRESSION INNER TUBE COMPANY, OF TULSA, OKLAHOMA, A CORPORATION OF DELAWARE.

DESIGN FOR A TIRE.

56,103.

Specification for Design.

Patented Aug. 17, 1920.

Application filed March 2, 1920. Serial No. 362,783. Term of patent 14 years.

To all whom it may concern:

Be it known that I, ANDREW J. PENNINGTON, a citizen of the United States, residing at Tulsa, in the county of Tulsa and State of Oklahoma, have invented a new, original, and ornamental Design for Tires, of which the following is a specification, reference being had to the accompanying drawings, forming a part hereof.

Figure 1 is a fragmentary plan view of a tire, showing my new design, and,

Fig. 2 is a transverse section taken on line 2—2 of Fig. 1.

I claim:

The ornamental design for a tire, as shown.

ANDREW J. PENNINGTON.
